UNITED STATES PATENT OFFICE

94,361

DESIGN FOR A CLOCK

Aaron Roth, Brooklyn, N. Y.

Application October 26, 1934, Serial No. 53,779

Term of patent 3½ years

To all whom it may concern:

Be it known that I, Aaron Roth, a citizen of the United States, residing at 570 Eastern Parkway, Brooklyn, in the county of Kings and State of New York, have invented a new, original, and ornamental Design for a Clock, of which the following is a specification, reference being had to

the accompanying drawing, forming part thereof,

Figure 1 is a front elevation of the clock showing my new design; and

Figure 2 is a side view thereof.

I claim:

The ornamental design for a clock, as shown.

AARON ROTH.
